UNITED STATES PATENT OFFICE.

LUIGI BUCCINI, OF ANSONIA, CONNECTICUT.

DEVICE FOR HANGING CURTAINS ON SINKS.

Application filed January 3, 1927. Serial No. 158,619.

This invention relates to a curtain and support therefor adapted to be applied to the outer edge of a wash tub, bath tub, wash bowl, and the like to hide the plumbing fixtures and give a neat and attractive appearance; and it is an object of the invention to provide a device of this character which will be simple in construction and may be easily and quickly applied, and which will be 10 neat and attractive in appearance.

With the foregoing and other objects in view, I have devised the constructions illustrated in the accompanying drawing as giving examples of the use and arrangement 15 of the device. In this drawing,

Fig. 1 is a front elevation of the upper portion of a wash tub, such as the so-called set tubs used for laundry purposes and showing my device applied thereto.

Fig. 2 is a vertical section thereof.

Fig. 3 is a similar view of the front of a wash bowl with my improved curtain support in position, and

Fig. 4 is a vertical section thereof.

Referring to Figs. 1 and 2, I have shown the device as applied to so-called laundry tubs or set tubs which usually have an inclined front wall 10 which may be composed of slate or any other suitable material 20 and ordinarily this tub is supported on legs, not shown, a suitable distance above the floor. I have provided a simple and easily applied means for mounting a curtain to extend from adjacent the upper edge of this 30 tub to the floor, or adjacent thereto, to enclose and thus hide the supporting means for the tub and also unsightly plumbing connections. This device comprises a sheet metal support 11, preferably of resilient 40 sheet metal, and when applied to this sort of device it is shaped to fit over and embrace the upper edge of the side wall 10. The inner portion 12 is preferably bent inwardly at its free edge 13 to engage the inner 50 surface of the tub and space the wall 12 somewhat from the surface of the tub. This gives a better appearance and causes the support to fit more accurately and more nearly the surface of the tub and prevents 60 any variation in the thickness of the edge of the tub causing the free edge of the inner portion 12 to curl outwardly away from the wall of the tub. It also puts the free edge in a position where it cannot injure the 70 user. The resilient action of the metal will

firmly clamp the wall of the tub and hold the device in position. On the outside of the tub the member engages the outer surface of the tub wall at the top thereof and is then preferably bent outwardly, as shown at 14, 60 and then inclined downwardly and inwardly, as shown at 15, to give a more attractive appearance and also to insure a better engagement of the device with the outer wall of the tub. The wall of the support is then 65 curved outwardly and upwardly to form a groove 16 open at its upper side, the free edge 17 of the support being curved inwardly somewhat so that the entrance to the groove is narrower than the widest portion of the groove. The curtain 18 may be of any suitable material and has secured to the upper edge thereof a filling element 19. This element may be fibre cord or a rubber tube or the like, and a convenient means of 70 securing it to the curtain is to wrap the curtain about this element and stitch the folded parts together, as indicated at 20. In applying the curtain to the support all that is necessary is to press this filling element into 75 the groove 16 formed in the support, when the resilient action of the sheet metal will securely clamp it in position. The curtain extends outwardly over the free edge 17 of the groove and depends therefrom, as shown 80 in Fig. 2, thus covering up the free edge and any elements below the support. The usual hinged cover for these tubs is shown 85 at 21, and in closed position may rest on the top of the support.

In Figs. 3 and 4, I have shown the device as applied to the depending outer wall 22 of a bath tub or a wash bowl. In this case the sheet metal support 23 is bent upon itself, as indicated at 24, to embrace and 90 clamp the lower free edge of this depending front wall, and this bent portion 24 is preferably somewhat wider at its lower part, as indicated in Fig. 4, so that variations in the thickness of the free edge will not interfere 95 with the proper engagement of the opposite sides of this bend with the inner and outer surfaces of the depending wall of the bowl. At its lower outer edge the support 23 is 100 curved outwardly and upwardly, the same as in the first form, to provide the groove 25 open at its upper side, and the free edge 26 of the sheet metal is curved inwardly the same as in the first form so that the entrance to the groove is narrower than the 105 110

body portion thereof. The curtain 18 is the same as in the first form and has a similar filling element 19 which may be forced into the groove and clamped therein by the resilient action of the metal, the same as in the first form. To insure that the support will remain in proper position it is better to employ in this form an additional clamp 27, which will assist the clamping action 10 of the support itself. This clamp may be simply a metal strap of substantially U-shape with the outer wall 28 engaging the outer wall of the bend 24 and the other wall extending upwardly on the inside of the 15 depending wall 22 and carrying a set screw 29 for clamping against the inner surface of the depending wall. Any number of these clamps may be used as is found desirable.

This curtain and its support is simple in 20 construction and may be easily and quickly applied, giving a neat and attractive appearance and covering up unsightly bowl or tub supports and plumbing connections.

Having thus set forth the nature of my 25 invention, what I claim is:

1. In a device for hanging curtains from a wash bowl, wash tub, in combination, a sheet metal support shaped to engage over the free edge of said bowl, tub and having 30 an outer portion curved to form a groove open at one side, the open side of the groove being of less width than an inner portion of the groove, and a curtain having a filling element secured along one 35 edge seated in said groove and held in the

groove by the resilient action of the walls of the groove.

2. In combination, a sheet metal support shaped to embrace the edge of a wash bowl, wash tub and curved at its outer edge to 40 provide a groove open at one side, and a curtain having a filling element secured along one side adapted to be seated in said groove and held by the resilient action of the sheet metal forming said groove. 45

3. In combination, a sheet metal support shaped to embrace the edge of a wash bowl, wash tub and curved downwardly and upwardly at its outer edge to provide a groove open at the top, the entrance to the groove 50 being narrower than the widest part of the groove, and a depending curtain having a filling element secured adjacent the top thereof, said cord being seated in the groove with the curtain extending over the outer 55 free edge of the groove and depending therefrom.

4. In combination, a support comprising resilient sheet metal shaped to embrace the free edge of a wash tub, wash bowl and 60 curved outwardly and upwardly at its outer edge to form an open groove, the open side of the groove being wider than the inner part thereof, and a curtain having a folded 65 edge, a filling element enclosed by said fold and seated in the groove with the curtain depending over the free edge of the groove.

In testimony whereof I affix my signature.

LUTIGI BUCCINI.
